UNITED STATES PATENT OFFICE.

CHARLES EDWARD HAVILAND, OF LIMOGES, FRANCE.

DESIGN FOR A DISH FOR TABLE-WARE.

SPECIFICATION forming part of Design No. 15,627, dated December 16, 1884.
Application filed March 14, 1884. Term of patent 14 years.

To all whom it may concern:

Be it known that I, CHARLES EDWARD HAVILAND, a citizen of the United States, residing in the city of Limoges, in the Republic of France, have invented and produced a certain new and original Design for Dishes for Table-Service, fully described and represented in the following specification and the accompanying drawings, forming a part of the same.

This design is applicable, in whole or in part, not only to the various dishes composing a table-service, but generally to ornamental dishes, whether flat or deep, and whether covered or not, and of rectangular or other shaped horizontal outline. It embraces two principal features—namely, a diaper figuring, and foliated stems or stalks which may be subdivided, and either of which may be embodied separately; or the two may be combined. Each, separately considered, whether subdivided or not, as hereinabove explained, and in combination, constitute essential elements of the design.

Embodiments sufficient to illustrate the application of the design are shown in the accompanying fac-similes, in which Figure 1 shows a flat dish or platter; Fig. 2, a flat dish or plate; Figs. 3 and 4, flat dishes or saucers; Figs. 5 and 8, deep dishes with covers; Figs. 6 and 9, deep dishes or tea-cups; Figs. 7 and 10, deep dishes or coffee-cups.

The diaper figuring is composed of two separate features—a panel conforming or suited to the outline of the dish, but centrally arranged, and an independent ribbon-like border, in like manner conforming or suited to the outline of the dish, but arranged between said panel and the edge of the dish. This panel is in turn composed of a center marked A and a border marked B in the fac-similes. The center A consists of a finely-defined pattern-work made up of symmetrical shapes producing diaper figures, while the border B is mainly composed of repeated spots that imitate hammered metal. These features are well defined in Figs. 1, 2, 3, and 4, where they form the ornamental surface of the shallow or flat dishes, while in Figs. 5 and 8 they are shown as forming the ornamental surface of the cover of the deep dishes.

In the bodies of the deep dishes of Figs. 5,

6, 7, 8, 9, and 10 the center A of the panel ornamentation, supposed to be involved by the bottom surface of the vessel, is omitted, and only the border B is apparent, the same following the lower surface of the sides of the vessels. The ribbon-like or independent border C is mainly composed of a body formed of star-like figures, (best seen in Fig. 1,) said border being continued around the vessel and conforming in direction to the general outline of the edge thereof. Thus in Figs. 1, 2, 3, and 4 it follows or is substantially parallel with the border-edges of the flat dishes shown, but ceases or vanishes where the overlapped corners are met. In the case of the covers in Figs. 5 and 8 the application is the same. In the case of the deep dishes, Figs. 5, 6, 7, 8, 9, and 10, it follows the upper edges of the dishes and vanishes wherever the overlapped corners are met. It need not be continuous, but may be broken up into sections, if desired, as may be the border B. The foliated main stem S is curved gracefully from a corner to or from the center, one or both sides of which main stem have demi-leaves 3 projecting therefrom. This main stem has one or more offshoots, T, and tendrils V, which in some instances are made up in part of leaf-like ornaments 6. The dish also has projecting from its other corners portions of foliated stems, as 2, in like manner ornamented with demi-leaves 3; but these ornaments 2 may be present or absent. The general body of the dish also has scattered over the plainer parts of the surface star-like ornamentations 1, that contrast with the other ornamentations, and these, whether arranged both within and without, or solely within or without, the panel A and its border B or the border C, and whether large or small, may be used or omitted, both as associated with both the panel A and its border B and the remaining part of the dishes, without modifying the scope of the design; but as associated with the main stem S they constitute a design subordinate to the main design.

The platter, Fig. 1, the plate, Fig. 2, the saucers, Figs. 3 and 4, and the dish and its cover, Figs. 5 and 8, serve to illustrate the general embodiment of the design, all being alike in general form and appearance, due to

the ornamentation. The cover of the dish and the cups, however, while embracing the design generically, also embody a subordinate design constituted by the shape or configuration of their handles. Thus in the instance of the dish-cover, Figs. 5 and 8, the main stem S is raised at the center of the dish-cover to stand high enough, as at 9, to form a handle, and yet preserve the harmony and character-
istics of the foliation. This is also the case with the handles of the cups (see Figs. 6, 7, 9, and 19) and with the side handles of the dish, (see Figs. 5 and 8); but in the dish body and cover the raised part of said stem largely involves a demi-leaf. In the case of the cups and the dish-cover, however, the stem S bows away from the surface, while in the case of the dish-body it simply projects therefrom. In the case of the body of the deep dish or cups the stem S practically starts from the corner, though, for the reason that the latter is truncated, the said stem appears to commence at a point nearer the center. Of course the foliated main stem S and its adjuncts, though shown as forming a single group, may be duplicated at opposite points without departing from the design.

The dishes represented are in general outline rectangular, but have truncated corners, and, as shown, the border C vanishes into said truncated corners. It is to be understood, however, that the center A B and the border C might be octagonal, to conform more exactly with the outline of the dish, or be circular or oblong, if such were the shapes of said dishes.

In the dish-cover and in the cups the body of the stem S is largely involved in the handle, while in the dish-body an enlarged demi-leaf, 3, mainly constitutes the handle. The center A and the border B of the panel and the ribbon-like border C are shown as made effective by the contrast of light and shade, while the stem S, its offshoots T, its tendrils V, the foliation 2, the demi-leaves 3, and the star-like ornaments 1 are colored to make them strongly contrast with the general surface and remaining ornamentation. The center A and border B are represented as depressed surfaces, and the remaining ornamentations are represented as raised surfaces. It is, however, immaterial how the design is produced, as any of the several ways of bringing out effects in artistic decorations may be employed.

The design constituting the central panel of

diaper figuring its border of repeated spots 55 imitating hammered metal, and the ribbon-like edged border and the scattered star-like ornaments; all separately and as associated together, are not claimed herein, except in the combinations set forth in the claims hereof, 60 but form the subject-matter of a separate application, No. 148,261, filed November 18, 1884.

What is claimed is—

1. In a dish, the design for the ornamentation of the same, which consists of a foliated main stem, S, a central panel of diaper figuring having a border, B, composed of repeated spots that imitate hammered metal, a ribbon-like border, C, and scattered star-like ornaments 1, substantially as shown and described. 65
2. In a dish, the design for the ornamentation of the same, which consists of a foliated main stem, S, and a central panel of diaper figuring having a border, B, composed of repeated spots that imitate hammered metal, substantially as shown and described. 75
3. In a dish, the design for the ornamentation of the same, which consists of a foliated main stem, S, and a central panel of diaper figuring, substantially as shown and described. 80
4. In a dish, the design for the ornamentation of the same, which consists of a foliated main stem, S, substantially as shown and described. 85
5. In a dish, the design for the ornamentation of the same, which consists of a foliated main stem at one corner and portions of foliated stems at the other corners, substantially as shown and described. 90
6. In a dish, the design for the ornamentation of the same, which consists of a foliated main stem, S, and scattered star-like ornaments 1, substantially as described. 95
7. The design for the handles of dishes, the same consisting of a foliated main stem, S, part of which is raised to project beyond the surface of the dish, substantially as shown and described. 100

In testimony whereof I have hereunto set my hand in the presence of two subscribing witnesses.

CH. ED. HAVILAND.
